CONVERSION OF HYDROCARBONS

Elmer R. Kanhofer, Chicago, Ill., assignor to Universal Oil Products Company, Chicago, Ill., a corporation of Delaware

No Drawing. Application June 30, 1939,
Serial No. 282,067

6 Claims. (Cl. 196—50)

This invention relates to the conversion of mixtures of hydrocarbons comprising olefin-containing distillates such as cracked gasolines, and relatively heavy straight run or analogous cracked distillate fractions boiling within the range of kerosene or gas oil.

More specifically, the invention is concerned with the treatment of such mixtures under selected conditions of operation in the presence of particular catalysts adapted to effect not only a decomposition of the heavier components of the mixtures to produce gasoline therefrom, but also to hydrogenate the olefins present in the original blend and those produced in the cracking operation so that a gasoline saturated in respect to the bromine number and consisting essentially only of paraffin and aromatic hydrocarbons is produced.

Cracked gasolines produced either by strictly thermal or thermal-catalytic processes contain varying percentages of olefinic hydrocarbons depending upon the type of stock cracked and the severity of the cracking conditions employed, high temperatures and low pressure having a tendency to produce relatively higher percentages of olefins. While such gasolines, particularly when stabilized against deterioration by the use of inhibitors, are entirely suitable for use in ordinary automobile engines, the requirements for fuels to be used in high compression airplane engines are much more severe since the slightest tendency toward gum formation or plugging of feed lines must be eliminated, while at the same time, the antiknock value must be high to insure maximum power output from the motors. These rigid requirements are met substantially only by isoparaffinic hydrocarbons and some aromatics and naphthenes which have low enough melting points either alone or in admixture with other hydrocarbons to prevent freezing at the low temperatures encountered at high altitudes. It is a particular object of the present invention to provide a process for producing substantially saturated high antiknock value motor fuels suitable for use in airplane engines.

In one specific embodiment, the present invention comprises the treatment of mixtures of cracked gasolines and distillate fractions of the nature of kerosene or gas oil by contacting said mixtures with granular catalytic material formed by calcining an alkali metal-free composite of precipitated silica hydrogel and precipitated hydrogels of alumina and/or zirconia either singly or in combination while employing temperatures within the approximate range of 500-800° F., pressure from atmospheric to approximately 200 lbs. per square inch, and relatively low liquid space velocities.

I have discovered that when mixtures of olefinic gasolines and gas oil fractions are contacted

with suitably chosen catalysts under the conditions specified that a number of simultaneous and concurrent reactions occur among the hydrocarbons so that not only are the olefins present in the cracked gasoline hydrogenated to produce the corresponding paraffins, but that the olefins in the gasoline produced by the cracking of the gas oil are also hydrogenated. Apparently some saturated constituents of the gas oils employed, probably naphthenes, undergo dehydrogenation to furnish hydrogen for the hydrogenation of the olefins to produce paraffins therefrom, thus producing on the one hand aromatics from the naphthenes and paraffins from the olefins, the blend of these two types of hydrocarbons having relatively high antiknock value and at the same time being free from olefinic and similarly reactive hydrocarbons. While not limiting the invention to the theory expressed, the following equation may be suggested as explaining the mechanism of the reaction.

Cyclohexane   Hexene   Benzene   Hexane

Obviously this reaction is only typical and will be accompanied by other less readily defined and more complex reactions involving the splitting of carbon-to-carbon bonds, isomerization, recombination of radicals, etc. In the equation, cyclohexane typifies naphthene hydrocarbons present in kerosenes or gas oils while the hexene typifies an olefinic constituent of a low boiling distillate of the nature of gasoline. While test work has indicated that the hydrogen for the saturation of the olefins comes principally from the naphthenic constituents of the gas oil and similar fractions, some hydrogen is undoubtedly gained from the dehydrogenation and cycling of various paraffinic constituents originally present and from the further dehydrogenation of the cyclic compounds produced. The overall effect uniformly observed, however, is that the gasolines produced by treating hydrocarbon mixtures of the type described consist predominantly of paraffinic and aromatic hydrocarbons, as indicated by relatively low bromine numbers as will be brought out in a subsequent section devoted to numerical data.

The process requires a relatively active catalytic material to be presently described, the use of temperatures materially below the ordinary cracking range of either strictly thermal or thermal-catalytic processes and moderately long times of contact with the catalyst. The reactions are further favored by increased pressure which assists the secondary hydrogenation reactions.

60 The catalysts which are preferred for use in

the present process are of a very specific character and require the use of an exact method of preparation.

According to the description of the preparation of the preferred catalysts given below, precipitated alumina hydrogel and/or zirconia hydrogel are composited with silica hydrogel, and then the composite is washed, dried, formed into particles, and calcined to produce a catalytic mass. However, the different catalysts which may be so produced do not necessarily give equivalent results.

In the following specification the terms "silica-alumina, silica-zirconia, and silica-alumina-zirconia" masses are used in a broad sense. Inasmuch as the chemical knowledge of the solid state has not been developed perfectly, it is not possible to give the structure of all solid substances. All that can be said definitely concerning these masses is that they contain silicon, oxygen, aluminum, and/or zirconium. Generally speaking, however, all these components show more or less low catalytic activity individually but in the aggregate display high activity. This activity is not an additive function, it being relatively constant for a wide range of proportions of the components, whether in molecular or fractions of molecular proportions. No one component can be determined as the one component for which the remaining components may be considered as the promoters according to conventional terminology, nor can any components be determined as the support and the others the catalyst proper.

In manufacturing the preferred catalysts in accordance with the present process it is necessary to employ silica which has been prepared by precipitation from solution as a hydrogel within or upon which the alumina and/or zirconia are deposited also by precipitation as hydrogels. The most convenient and ordinary method of preparation of a satisfactory silica gel is to acidify an aqueous solution of sodium silicate by the addition of the required amount of hydrochloric acid. The excess of acid and the concentration of the solution in which the precipitation is brought about will determine the eventual primary activity of the silica and its suitability for compositing with the alumina and/or zirconia hydrogels to produce a catalyst of high activity. In general, the most active silica is produced by adding only enough acid to cause gel formation to occur in the sodium silicate, but the material formed at such a point is rather gelatinous and is filtered with difficulty. Further the silica hydrogel is coagulated incompletely at this point. By adding a moderate excess of acid after the hydrogel has formed, the more desirable physical characteristics in regard to catalyst activity are conserved while the "filtrability" is generally improved and the silica hydrogel is precipitated more completely. Fairly good hydrated silica for present catalytic purposes may be made by employing as high as a 20% excess of hydrochloric acid, but beyond this point the more desirable properties are lost. After precipitating the silica gel it is preferably washed until substantially free from salts by using several alternative reagents, which will be described later.

In one mode of preparing the activated form, 70 the silica hydrogel may be boiled either with separately precipitated aluminum hydroxide and/or zirconium hydroxide gel, which is added in the wet condition to the silica suspension, or the silica hydrogel may be suspended in and 75

boiled within an aluminum chloride or the silica gel may be treated similarly by an aqueous solution containing both aluminum and zirconium salts. In either case the final precipitate comprising essentially the hydrated silica and hydrated alumina and/or zirconia is finally washed to substantially complete removal of water soluble materials and dried at about 300° F. to produce a rather crumbly and granular material 10 which may be ground and pelleted or sized to produce particles of catalyst. Since this material is calcined at a temperature in the approximate range of 1000-1500° F. and is used at a temperature of the order of 500-900° F. its water content 15 is further reduced until after a brief period of service it amounts to about 2-3% by weight of the catalyst particles.

The necessary hydrogel of alumina or zirconia or a mixture of such gels is preferably deposited 20 on washed alkali metal-free silica gel by adding an alkaline precipitant such as ammonium hydroxide, ammonium carbonate, or ammonium sulfide to aqueous solutions of aluminum and/or zirconium salts, followed by suitable washing to 25 remove impurities. The alumina and/or zirconia hydrogels may be precipitated from such solution in which previously prepared and washed hydrated silica is suspended, followed by a washing of the total composite precipitate. Similarly, 30 purified silica may be suspended in a solution of an aluminate, such as sodium aluminate and alumina precipitated by the addition of the aluminum salts or by the requisite quantities of acid. As a further alternative method of producing the desired catalysts, aluminum and/or zirconium salts may be added to a solution of an 35 alkali metal silicate to jointly precipitate silica hydrogel with the hydrogels of alumina and/or zirconia and further amounts of silica hydrogel 40 may then be precipitated by the addition of acid. A characteristic equation illustrating the preparation of a silica-alumina catalyst is given below, although in it no account is taken of water of hydration:

It will be obvious that the employment of the reaction shown in the above equation will be limited on account of the molal proportions involved so that such a method of preparation of a composite may need supplementing by the presence or further precipitation of silica to obtain the desired ratio.

A specific and satisfactory method of preparing 55 silica-alumina catalysts used in accordance with the present invention is given below, although not with the intention of unduly limiting the proper scope of the invention. By following the procedure outlined with a suitable choice of reagents 60 of accepted purity, good catalysts for nearly all cracking reaction may be produced.

In the finished catalysts, prepared as indicated above, the weight ratio of silica to alumina and/or zirconia may vary within a considerable range, 65 for example from 30 to 0.1, although as a rule catalyst composites having optimum activity based on yields and quality of gasoline produced will correspond to silica-oxide weight ratios of the order of about 30 to 10 in which the term "oxide" is used in reference to alumina and/or zirconia. These proportions will vary considerably with the particular fractions subjected to treatment and the degree of conversion found to be optimum in any particular case.

It is to be recognized that very little is known

positively concerning the mechanism of enhanced activity of complex catalysts and no attempt will be made herein to offer any definite reasons for the observed mutually promotional effect of silica with alumina and/or zirconia composites prepared for catalytic purposes according to the present invention. There may be a catalytic effect due to the juxtaposition of the catalyst components and it may be that the oxide (alumina and/or zirconia) is the more active catalyst and is extensively dispersed in and on the silica in order to present a large surface.

The following numerical data is given in support of the value of the present process although not with the intention of imposing undue limitations on the proper scope of the invention.

Blends were made of a gasoline produced by thermally cracking an East Texas gas oil and further quantities of the gas oil itself. These blends were passed through a silica-alumina-zirconia composite catalyst under conditions indicated in the appended table. The catalyst was prepared by the general procedure outlined in the preceding specification and consisted of approximately 100 molar proportions of silica, 2 molar proportions of alumina, and 4 molar proportions of zirconia. In the table, A refers to the cracked gasoline, and B to the gas oil.

Octane number+6 cc. tetraethyl lead.....		

It will be seen from the above table that in about the first hour of operation in the runs made either at 800 or 700° F. that the bromine numbers were very low on the material boiling below 300° F. It will also be seen that the yield of this material was very high for the first hour although the yield in the second half hour was somewhat lower than the yield in the first half hour.

It is further seen that the 400° F. endpoint material in the products from run No. 1 and particularly the 300° F. endpoint material from the products of run No. 2 at the lower tempera-

ture had a considerably increased susceptibility to the action of tetraethyl lead. In the place of the last mentioned 300° F. endpoint material, the octane number was three points lower than the corresponding material in the charge, but was nine points higher when the same amount of tetraethyl lead was added. The low bromine numbers indicate substantially complete saturation and absorption of material amounts of olefins or diolefins, either of a straight chain or cyclic character.

It is obvious from the above that the best results in the present type of process are obtainable with short periods of operation with a relatively fresh and active catalyst. These conditions are met by running for short periods and then reactivating by burning off traces of carbonaceous deposits and this feature is comprised within the scope of the present invention.

I claim as my invention:

1. A process for producing motor fuel of high anti-knock value and relatively low olefin content which comprises combining olefinic gasoline with a hydrocarbon oil heavier than gasoline and containing a substantial proportion of saturated hydrocarbons, and subjecting the resultant mixture to the action of a catalyst comprising a calcined mixture of precipitated silica hydrogel and precipitated alumina hydrogel at a temperature in the approximate range of 500-800° F. for a contact time sufficient to convert a substantial portion of said heavier oil into gasoline and to effect substantial saturation of gasoline boiling olefins.

2. A process for producing motor fuel of high anti-knock value and relatively low olefin content which comprises combining olefinic gasoline with a hydrocarbon oil heavier than gasoline and containing a substantial proportion of saturated hydrocarbons, and subjecting the resultant mixture to the action of a catalyst comprising a calcined mixture of precipitated silica hydrogel and precipitated zirconia hydrogel at a temperature in the approximate range of 500-800° F. for a contact time sufficient to convert a substantial portion of said heavier oil into gasoline and to effect substantial saturation of gasoline boiling olefins.

3. A process for producing motor fuel of high anti-knock value and relatively low olefin content which comprises combining olefinic gasoline with a hydrocarbon oil heavier than gasoline and containing a substantial proportion of saturated hydrocarbons, and subjecting the resultant mixture to the action of a calcined mixture of precipitated hydrogels of silica, alumina and zirconia at a temperature in the approximate range of 500-800° F. for a contact time sufficient to convert a substantial portion of said heavier oil into gasoline and to effect substantial saturation of gasoline boiling olefins.

4. The process as defined in claim 1 further characterized in that said hydrocarbon oil is a straight run naphthenic petroleum fraction.

5. The process as defined in claim 2 further characterized in that said hydrocarbon oil is a straight run naphthenic petroleum fraction.

6. The process as defined in claim 3 further characterized in that said hydrocarbon oil is a straight run naphthenic petroleum fraction.

ELMER R. KANHOFER.
